W. AUGUSTIN,
RETURN-TO-ZERO DEVICE FOR CALCULATING MACHINES.
APPLICATION FILED APR. 2, 1913.

UNITED STATES PATENT OFFICE.

WILHELM AUGUSTIN, OF CHARLOTTENBURG, GERMANY.

RETURN-TO-ZERO DEVICE FOR CALCULATING-MACHINES.

1,086,344.

Specification of Letters Patent.

Patented Feb. 10, 1914.

Application filed April 2, 1913. Serial No. 758,317.

To all whom it may concern:

Be it known that I, WILHELM AUGUSTIN, a citizen of the Empire of Germany, residing at Charlottenburg, in the Empire of Germany, have invented a new and useful Return-to-Zero Device for Calculating-Machines, of which the following is a specification.

My invention relates to calculating machines and especially to improvements in the mechanism of such machines connected with the result indicators, whereby such mechanism is, when required, brought back to the zero position.

Under the present invention the setting or starting levers of calculating machines are brought back to the zero position by means of a suitably shaped disk fitted on the registering shaft of the result mechanism. The disk actuates an intermediate gear which, in turn, puts pawl mechanism out of gear so that the result spindle can be easily and conveniently brought back to the zero position by means of a thumb screw or the like.

It is a well known fact that with calculating machines, such for instance as disclosed in British Patent No. 28465 of 1910, the several result indicating wheels and coöperating parts are temporarily maintained in the position to which they have been set, by brakes or other retaining elements that are influenced by comparatively strong springs. It is therefore obvious that whenever the result indicators, etc., are returned

to their zero position, the retaining members not only greatly impede such operation, thus necessitating the expenditure of a large amount of manual labor, but they also cause a quick wearing out of the parts. By my invention, this difficulty is effectively overcome, for which purpose the retaining members are so constructed that they are brought out of engagement with their coöperating elements as soon as the return movement of the indicators has been started.

In the accompanying drawing: Figure 1, is a cross section through a device embodying my invention, and Fig. 2, a plan thereof.

Upon the calculating shaft Y, carrying winged nut Z are mounted the toothed calculating wheels W, which may be rotated independent of said shaft, one of such wheels only being shown in the drawing. Wheel W is adapted to be engaged by a retaining pawl J fulcrumed at X⁴ and provided with a heel J¹ extending beyond said fulcrum. Upon shaft Y is further firmly mounted a cam disk X having a flattened section x, said cam disk being engaged by a lever X¹ fulcrumed at X². The rear arm of lever X¹ carries a stud or abutment X³ that engages the lower side of heel J¹.

For returning the wheel W to its zero position, nut Z is rotated so as to cause shaft Y to be moved in an axial direction until it becomes coupled to the wheel (said well known coupling etc. mechanism being not shown as not forming part of the present invention). As cam X participates in this rotation of shaft Y, said cam will swing the forward end of lever X¹ downward, so that stud X³ is raised to tilt pawl J out of engagement with wheel W. During the continued rotation of the shaft Y, the calculating wheel is thus freely returned to its zero position. After the rotation of shaft Y has been completed, disk X will occupy its original position, so that lever X¹ engages the flattened disk section x and stud X³ is lowered to permit a reengagement between the pawl J and wheel W.

I claim:

A return-to-zero device for calculating machines comprising a rotatable shaft, a cam disk fast thereon, a lever having a heel and engaging said disk, a toothed wheel carried by the shaft, a pawl adapted to engage said wheel, and an abutment on the pawl that engages the lever-heel.

WILHELM AUGUSTIN.
